UNITED STATES PATENT OFFICE.

JOSEPH R. HEBERT, OF BROOKLYN, NEW YORK, ASSIGNOR TO ELIAS A. WILKINSON, OF NEWARK, NEW JERSEY.

TAKE-UP FOR SEWING-MACHINES.

SPECIFICATION forming part of Letters Patent No. 268,668, dated December 5, 1882.

Application filed May 6, 1882. (No model.)

To all whom it may concern:

Be it known that I, JOSEPH R. HEBERT, of Brooklyn, New York, have invented a new and useful Improvement in Take-Ups for Sewing-
5 Machines, described in this specification and the drawings thereof.

The invention consists in improvements relating to the mechanism in connection with the needle-bar for taking up the slack in the
10 upper thread in sewing.

Figure 1 is a view of one form of the improvements from the inner side of the face-plate, detached from the machine. Fig. 2 is a side view of the same. Fig. 3 is a view similar
15 to that of Fig. 1, except that the needle-bar driving-pin moves in a guide.

In the form of construction shown two bosses, A B, are cast on the inner side of the face-plate C, in the recess D thereof. To the
20 boss A is pivoted, by a screw, *a*, a cam-arm, E, having a cam-face, *b*, of the form shown, and a slot, *c*, at the lower end. The needle-bar F has one half of its bearings in slots *d d* in the ends *e e* of the face-plate, and has an inwardly-
25 projecting pin or driving device, *f*, on which there is an anti-friction roll, *g*, to operate against the cam-face *b*, and give to the cam-arm lateral motion as the needle-bar is actuated up and down in sewing. To the boss B is pivoted, by
30 a screw, *h*, a take-up lever, G, having a pin or connection, *i*, to operate in slot *c* of the cam-arm E, to form a joint and receive motion from the cam-arm to operate the take-up lever, which has a thread or take-up finger, *k*, at its
35 upper end, extending through the slot *m* in the face-plate. The loose slot-and-pin connection of the cam-arm and take-up lever is preferably made at a point below the cam-face *b* of the cam-arm, which is engaged by the operating pin or device on the needle-bar. By connecting these parts in this manner the pin *i* on the take-up lever is necessarily brought so near the fulcrum of the lever and so far from the fulcrum of the cam-arm that a comparatively slight movement of the cam-arm will suffice to give the necessary movement to the take-up finger *k*, located at the free end of the take-up lever, to enable the finger to perform its proper function. As the cam-face *b* of the
45 cam-arm is in constant contact with its operating device on the needle-bar, an easy and

nearly-constant movement will be imparted to the take-up lever.

When the needle-bar is in operation a lateral vibrating motion is communicated to the cam-arm, which communicates a like motion to the take-up lever. The driving device on the needle-bar causes the motion in one direction, and the spring H, fastened to the face-plate and connected to the take-up lever, causes the motion in the other direction. The take-up finger on the upper end of the take-up lever operates or vibrates in the slot in the face-plate to take up the slack thread in sewing. The take-up lever is arranged to project upward, and the take-up finger is near the upper end of the face-plate. This arrangement prevents the dripping of the lubricant upon the work.

The details of construction and operation may be varied within the scope of the improvements. For example, the cam-arm may be provided with a cam-slot for the needle-bar driving device to operate in, as shown in Fig. 3, to give both movements to the cam-arm.

I make no claim herein to a slotted cam-arm on the inner side of a face-plate and projecting upward, combined with a pendent take-up lever on the outside thereof.

I claim as my invention—

1. The combination, in sewing mechanism, of a face-plate, C, having slot *m*, a pendent cam-arm, E, pivoted inside thereof, and having a cam-face, *b*, an upwardly-projecting take-up lever, also pivoted inside the face-plate, and having a take-up finger, *k*, projecting outward through the slot, the cam-arm and take-up lever being loosely connected below the cam-face, a needle-bar, F, having driving-pin *f*, working against the cam-face, and a retracting-spring, H, holding the cam-arm against the driving-pin, substantially as set forth.

2. The combination, adapted to sewing mechanism, of a face-plate, a pendent cam-arm pivoted inside the face-plate and having a cam-face, an upwardly-projecting take-up lever, also pivoted inside the face-plate, and having a take-up finger projecting outward through a slot therein, the cam-arm and take-up lever being loosely connected below the cam-face, a needle-bar having an anti-friction driving device to work against the cam-face, and a

retracting-spring to hold the cam-arm against the driving device, substantially as set forth.

3. The combination, adapted to sewing mechanism, of a face-plate having a slot, a pendent cam-arm pivoted inside the face-plate and having a cam-face, an upwardly-projecting take-up lever, also pivoted inside the face-plate, and having a take-up finger projecting outward through the slot, the cam-arm and take-up lever being loosely connected below the cam-face, a needle-bar adapted to operate the cam-arm in one direction, and a retracting-spring to operate the cam-arm in the opposite direction, substantially as set forth.

15 4. The combination, in sewing mechanism, of a face-plate having a slot, a pendent cam-arm adapted to vibrate inside the face-plate, an upwardly-projecting take-up lever, also adapted to vibrate inside the face-plate, and 20 having a take-up finger projecting outward through the slot, the cam-arm and take-up

lever being loosely connected below the operating part of the cam-arm, and a needle-bar adapted to operate the cam-arm, substantially as set forth.

25 5. The combination, in sewing mechanism, of the face-plate having a slot, a cam-arm to vibrate inside the face-plate, a projecting take-up lever operated by the cam-arm, and also arranged to vibrate inside the face-plate, and 30 having a take-up finger projecting outward through the slot, and a needle-bar to operate the cam-arm, substantially as set forth.

In testimony whereof I hereunto subscribe my signature and affix my seal, in the presence 35 of two attesting witnesses, on the 21st day of April, 1882.

JOSEPH R. HEBERT. [L. S.]
